CLAIM

(22) Filed: **Sep. 13, 2000**

We claim the ornamental design for building structure for
self-serve car wash, as shown and described.

(51) LOC (7) Cl. **25-03**

DESCRIPTION

(52) U.S. Cl. **D25/34**

FIG. 1 is front elevational view of a building structure for
self-serve car wash showing our new design;

(58) Field of Search D25/1, 4, 22, 33,
D25/34, 29; 52/79.1, 79.4, 79.9, DIG. 17;
134/123, 45; 15/DIG. 2; D32/4

FIG. 2 is a rear elevational view thereof;

(56) **References Cited**

FIG. 3 is a left side elevational view thereof;

U.S. PATENT DOCUMENTS

FIG. 4 is a right side elevational view thereof;

D. 239,701 * 4/1976 Baker D25/34
D. 327,744 * 7/1992 Francis D25/1
D. 344,345 * 2/1994 Goldberg D25/34

FIG. 5 is a top plan view thereof; and,
FIG. 6 is an enlarged partial right side perspective view
thereof.
